US00D410628S

United States Patent [19]

[19]

Wu

[11] Patent Number: Des. 410,628

[45] Date of Patent: ** Jun. 8, 1999

[54] ELECTRICAL CONNECTOR

5,707,245	1/1998	Yamamoto et al.	.....	439/159 X
5,791,920	8/1998	Tomioka et al.	.....	439/159
5,795,190	8/1998	Ono	.....	439/607
5,816,826	10/1998	Colemen	.....	439/79 X

[75] Inventor: **Kun-Tsan Wu**, Tu-Chen, Taiwan

Primary Examiner—Joel Sincavage

[73] Assignee: **Hon Hai Precision Ind. Co., Ltd.**,
Taipei Hsien, Taiwan

[**] Term: 14 Years

[21] Appl. No.: 29/087,427

[22] Filed: May 1, 1998

[30] Foreign Application Priority Data

Nov. 3, 1997 [TW] Taiwan 86309561

CLAIM

The ornamental design for an electrical connector, as shown and described

DESCRIPTION

FIG. 1 is a perspective view of an electrical connector showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a perspective view of an embodiment of the electrical connector shown in FIG. 1 with an electronic card inserted therein.

The broken line showing of the electronic card is included for the purpose of illustrating environmental structure only and forms no part of the claimed design.

1 Claim, 8 Drawing Sheets

FIG. 1

FIG.2

FIG. 3

FIG. 4

FIG. 5

FIG. 6

FIG. 7

FIG.8
